UNITED STATES PATENT OFFICE

120,721

DESIGN FOR A COMBINATION HOOD AND MUFFLER

Baruch Posin, New York, N. Y.

Application October 17, 1939, Serial No. 87,703

Term of patent 3½ years

To all whom it may concern:

Be it known that I, Baruch Posin, a citizen of no country, residing at New York, in the county of New York, city and State of New York, have invented a new, original, and ornamental Design for a Combination Hood and Muffler, of which the following is a specification, reference being made to the accompanying drawing, forming a part thereof.

Fig. 1 is a side perspective view of a combination hood and muffler showing my new design.

Fig. 2 is a perspective view thereof, as viewed from the front and in closed condition.

I claim:

The ornamental design for a combination hood and muffler, substantially as shown.

BARUCH POSIN.
